UNITED STATES PATENT OFFICE.

LEWIS E. MORRISON, OF NEWARK, NEW JERSEY, ASSIGNOR TO AMERICAN TYPE FOUNDRERS COMPANY, A CORPORATION OF NEW JERSEY.

SHEET-FEEDING MECHANISM.

Original application filed April 9, 1925, Serial No. 21,777. Divided and this application filed February 6, 1926. Serial No. 86,871.

This invention relates to improvements in paper feeding mechanisms of the type disclosed in my pending U. S. patent application Serial Number 21,777, filed April 9, 1925, 5 from which this application is divided.

The said pending application discloses an automatic feeder especially adapted for use with a Golding platen press, though not limited to such use.

10 The present invention has reference to certain improvements involving a paper feeding device not restricted in its use to any particular type of printing press or other machines and the objects of the present invention are to generally improve paper feeding devices, the novel features of which will appear more clearly as this specification proceeds.

15 The invention is illustrated in the accompanying drawings in connection with a Golding printing press as a mere example of a machine for which the feeder is adapted. In the drawings:

20 Figure 1 is a right hand view of a Golding press equipped with a feeder embodying the invention. The feeder is illustrated diagrammatically with details omitted and parts broken away.

25 Figure 2 is a detail left hand view of parts of the feeder.

Figure 3 is a front view of the feeder.

30 Figure 4 is an enlarged right hand side view of the feeder mechanism parts being broken away.

35 Figure 5 is a rear view of one side of the feeder looking in the direction of the arrow 5 in Figure 4.

40 Figure 6 is a view similar to Figure 4 but shows the feeder in feeding position with parts in section and other parts broken away.

Figure 7 is a left hand side view of parts of the mechanism for feeding the paper to the proper height for separation.

Figure 8 is a rear view thereof.

45 Figure 9 is an inside detail view of parts shown in Figures 7 and 8.

Figure 10 is a view in continuation at the top of the parts shown in Figure 8.

50 Figure 11 is a detail view of the paper raising mechanism or pile elevator.

Figure 12 is a detail view showing the parts operating the pile elevator.

Throughout this specification reference is made to the aforesaid pending application,

and the reference characters in the drawings 55 are identical with the reference characters used in the pending application. The Golding press is so well known in the art that no particular description or illustration thereof is required. It is sufficient for the purposes of 60 this invention to identify the press in Figure 1 by the frame 1, the form 2 and the platen 3.

The automatic feeder comprises suitable supporting means 9 secured to the press or other machine. 10 is the feeder base. As described in said pending application, the entire feeder is adapted to be swung to one side for purposes of accessibility to the main machine.

Before entering upon a detailed description 70 of the several parts, the general operation had better be understood and is as follows: In Figure 1 the feeder is shown in normal operative relation to the press. On the opening of the platen a sheet of paper is separated 75 from the pile 30 by suction pickers 31, and as the platen swings down the feeding mechanism swings towards the press to deposit a sheet on the platen, see Figure 6. If a sheet has previously been printed the delivery 80 gripper 109 seizes it and as the feeder swings back into normal position, the delivery gripper removes the printed sheet from the platen and deposits it in the delivery box 16.

The pile of sheets of paper 30 rests on a 85 paper elevator platform 11. The top sheet of paper is separated by suction pickers 31, carried by hollow arm 32 mounted in bearings 39 which are adjustably clamped to a picker shaft 41 by wing nuts 42, Figure 3. 90

Suction is applied to the pickers through suitable hose connections 44 leading in a well known manner to a suction pump not shown. These parts are fully described in the said pending application. 95

The picker shaft 41 is journaled in two upright arms 46, 46, one on each side of the feeder. The arms 46 are pivoted at their lower ends at 47 to levers 48 and 49, Figures 1 and 2. The lever 48 is formed with a 100 cam 50.

The two levers 48 and 49 with the parts carried thereby constitute a separator carriage pivoted on the separator arms 53 and 54. The carriage rests by gravity on stops 69 and 70 105 secured to the separator arms, one on each side.

During the separation of the feeder suc-

tion is applied to the pickers which are caused to descend upon the top sheet by a suitable mechanism, not shown herein, to pick up the top sheet, after which the separator carriage 5 is swung toward the platen by the separator arms 53 and 54, which are pivoted at their lower ends on a shaft 99 journaled in the frame 80 and 90. To this end, each of the arms is connected by a link 100 to the gripper arms 101 and 102. These latter are carried on a shaft 103 supported on the base 10.

The receptacle 16 is carried by suitable supports 180, 180 at the front of the press, At the rear edge or entrance into the box 16 15 there is journaled a shaft 181 which carries two uprights 182, 182. A bar 183 is fixed to the upper ends of the uprights 182 and said bar carries sheet guiding and supporting fingers 184 in the form of curved wires.

20 At each side of the box 16 there is also supported a shaft 185 which carries thin rubber disks 186. The shaft 185 is adapted to be driven by a belt 187 from a turbine shaft 201 supported underneath the box 16. The 25 turbine shaft carries a turbine or wind wheel 188 within a cylindrical casing 189. The shaft 181 carries an arm 190 connected with a cable 191 to another arm 192 secured to the shaft 99 to which the separator arms aforesaid are secured. This feature is shown clearly in Figure 1. One of the said uprights 182, Figure 4, carries a stop 193 which is held against the one support 194 for the said shaft 185 by a spring 202 coiled around the shaft 181, Figure 3.

To the aforesaid fixed frames 80 and 90, Figure 6 there is pivoted at 195 on each side of the feeder a lever 196 which extends towards the platen. The free ends of the levers 40 196 are joined by a shelf 197 having side guides 198. From the levers 196 links 199 extend downward. The lower ends of the links are pivoted at 200 to the aforesaid arm 192.

45 In operation when the platen is closed the delivery mechanism elements are in the positions shown in Figures 1 and 6. The sheet fingers 184 are held in over the delivery box 16 by the spring 202 which tends to rotate the shaft 181 anticlockwise, the stop 193 resting against the support 194. The turbine 188 is not running.

Referring now to Figure 6 it will be seen that as the platen moves down into sheet receiving position, the levers 196 are lowered on their pivots 195 by the links 199 which are moved down due to the downward movement of the arm 192 on the shaft 99, Figure 1, which shaft is moved clockwise in said figure.

60 Consequently the shelf 197 is lowered just past and slightly below the platen as in Figure 6 to bridge the gap between the platen and the delivery box. At the same time, however, the shaft 181 has been rotated clockwise in Figure 6 by the cable 191 and arm 190

against the action of the spring 202 to open up, as it were, or move towards the platen, the sheet guiding fingers 184. The combined effect of these movements is, that as the printed sheet is removed from the platen in over the shelf 197 and fingers 184 and towards the delivery box, said shelf and fingers are raised and support the body of the sheet, the delivery edge of which is held by the grippers, and raise the rear portion of the sheet so that the latter is evenly and smoothly delivered into the box 16. If it is desired to impart to the sheet a quick motion into the box 16, the turbine 188 is operated to rotate the shaft 185 and rubber disks 186 (in contact with which the sheet is being delivered) to cause said rubber disks to frictionally engage the sheet to speed it on its way into the box 16. This is a very necessary feature with thin and large sheets to get them quickly out of the way and prevent them from being blown about. The numeral 203 in Figure 5 indicates the delivered sheets in the box 16 in which they are jogged into final position.

In order to operate the feeder rapidly to supply the platen with paper, it is necessary that the stack of paper 30 in the feed box or support 11 be kept up to a certain level to cooperate properly with the separating mechanism. This is accomplished by the pile elevator mechanism.

The pile elevator, Figures 3, 6 and 7 to 12 inclusive comprises the elevator platform 11, upon which the paper rests, carried by two supports 220, 220 mounted to slide vertically in the fixed frames 80 and 90 on each side of the feeder at the front thereof. The lower ends 221 of the supports are connected by cables 222 to a ratchet 224 on a winding shaft 223 suitably journaled on said frames. To the shaft is secured a ratchet 224 which is engaged by a pawl 225 to rotate the shaft 223 to wind up the cables to lift the elevator. The pawl is pivoted at 226 to an arm 227 which is operated once to each feeding stroke of the feeder by means of a link 228 pivoted at 229 to the separator arm 53, Figure 12. The link 228 is connected to the arm 227 by a pin 230 and slot 231 connection so that the said shaft 223 will be rotated to lift the elevator towards the end of the feeding stroke when the separating mechanism is clear off the paper 30.

It is obviously undesirable and almost impossible to lift the elevator for each sheet removed from the pile of paper 30, because the lifting movement is necessarily greater than the thickness of a sheet of paper. Means are therefore provided for controlling the operation of the actuating pawl 225 aforesaid so that it will engage the ratchet 224 only when the pile of paper 30 has been depleted to a certain low level below the pickers 31.

This is accomplished by a feeler 531, Figure 3, which is adapted to rest upon the paper

by gravity, said feeler being secured to an arm 232 mounted on the upper end of a pawl controlling rod or member 233 which slides within a guiding tube 234. The lower end 5 of said controlling rod 233 is adapted to cause the engagement of the pawl 225 with the ratchet 224. Normally the pawl 225 is disengaged from the ratchet by gravity in that the pawl of its own weight falls away 10 from the ratchet until stopped by the pawl stop 235 which carries a pin 236. To the frame 80 is pivoted at 237 a balanced lever 238 which carries a shelf 239 which extends in over and rests on the said pin 236.

15 When the feeler 531 has moved down on top of the paper 30 to a level which requires the paper to be elevated, the control rod 233 is caused to drop upon the shelf 239 to depress shelf 239 to tip the pawl 225 into engagement with the ratchet 224.

It is obvious, however, that the feeler 531 cannot be left to rest on top of the paper with the weight of the control rod 233 because such a condition would prevent the separation of the top sheet. Means are therefore provided for normally taking the weight of the control rod off the paper at the time separation takes place and between each separation the control is permitted to drop, so that 30 if the control drops to paper level between separation it will cause the engagement of the pawl and ratchet as aforesaid.

To this end the control rod carries a dog 240 which extends through a slot 241 in the tube 234. Said dog is adapted to rest on a stop 242 carried by a slide 243 on the side frame 80. The stop slide 243 rests by gravity on the upper end 244 of a stop control member 245, the slide having an abutment 40 246 for this purpose. The stop control 245 is in turn carried by a link 256, which is pivoted at 257 to the separator arm 54. The link 256 has two stop screws 247 and 248, and the stop control has two slots 249, 249 45 through which said screws project. A strong spring 250 is interposed between the stop control 245 and the screw 248 in the link 256 and tends to pull the stop control upwardly with respect to the link, or in other words, 50 the spring 250 keeps the upper end of the stop control 245 up under and against the abutment or screw 246. The link 256 also has a slot 251 which rides on the abutment screw 246 aforesaid. The stop slide 243 is 55 guided by screws 252 in slots 253.

The entire operation of the pile elevator mechanism and the controlling means therefore is as follows:

When the separator carriage moves toward 60 the platen with a separated sheet, the link 256 is pulled down also, its screws 247 and 248 moving in the slots 249. But this movement of the screws does not affect the position of the stop control 245 because the relative 65 sliding movement of the link 256 with respect

to the stop control 245 is compensated for in the spring 250 which still keeps the end 244 of the stop control up under and against the abutment screw 246.

When, however, the link screws 247 and 248 have reached the bottoms of the slots 249, the continued movement or pull of link 256 causes the stop control 245 to move downward away from the abutment screw 246, thus permitting the stop 242 to drop away 75 from under the dog 240. Hence the latter and the feeler control are free to drop within the tube 234.

The relative movements of the stop 245 and the link 256 are provided to insure 80 against premature downward movement of the feeder control on the top sheet.

If there is sufficient paper in the pile 30, the feeler control will not be able to drop all the way down on the shelf 239 to tilt the pawl 225 into engagement with the ratchet 224 to raise the elevator, and in such case the feeler will simply drop on the paper, and when the separating carriage returns, the stop slide 242 will be moved upwards under the dog 240 by the reverse movement of the link 256, and thereby lift the dog and feeler off the paper.

If the paper need to be raised, the control rod will fall down on the shelf 239, the pawl 225 will be tilted and as the separator arm 53 moves forward on the next feeder stroke. Figure 12, the ratchet 224 will be rotated to turn shaft 223 and the elevator will be 100 raised.

The upper end of the cable 222 is wound around the shaft 223 and then secured to the ratchet 224. The numeral 255 denotes a stop pawl for the ratchet 224. A handle 258 is adapted to be swung upward to raise said 105 stop pawl when the shaft 223 will be rotated by the weight of the elevator acting on the cables 222. 259 is a handwheel, Figure 3, for rotating the shaft 223 by hand.

260 is a forked guide on top of tube 234. 110 The feeler arm 232 is guided in said guide in proper position in over the paper. The guide 260 is frictionally adjustable on tube 234.

In the aforesaid pending application there 115 is disclosed a pneumatic system for the complete operation of the feeding attachment including the pneumatic pickers, the tripping mechanism of the press and several other submechanisms. For the purposes of the 120 present application it is sufficient to note that the shaft 103 to which the gripper arms are secured is operated by means of an arm 314, Figure 1, which in turn is attached to the piston rod 313 of an air driven engine or cylinder 125 311. The latter is fully disclosed in the pending application referred to above. Also that in Figure 4 the numeral 324 denotes a pipe through which air is blown into the turbine 188. 130

Referring now to the means of applying suction to the pneumatic pickers 31, the reference numeral 294, Figure 4, denotes a slide valve body suitably supported on the separator arm 53 (which carries the separators together with the arm 54). Within the body 294 moves a slide valve 293 which has a port 294. The slide valve is operated by a link 308 pivoted on the gripper supporting arm or post 101. The link 308 is adjustably carried within a pivoted guide 335 and the link is adjustable by a nut 334. The pipe 44 leading from the pickers communicates with the port 294, and another pipe 331 leads from the valve 292 to the pump and forms a continuation of the pipe 44.

At the start of the feeding movement, suction is applied to the pickers 31 from the pump by way of pipes 331, valve port 294 and pipes 44. But the feeding movement, that is the swing of the feeding elements towards the platen, operates the slide valve to cut off the pipe 331 (the valve moving inwardly in the body 292) and open up pipes 44 to the atmosphere, thus breaking the vacuum in the pickers so that the separated sheet may be dropped on the platen in an obvious manner. On the return stroke the slide valve is again operated to establish communication between the pickers and the pump.

The feeder as herein disclosed has been tested and in practice has solved the problem

of feeding a Golding press, and while arranged and designed in connection with a Golding press, nevertheless the invention is not limited thereto as is obvious, and changes and modifications may readily be made by those skilled in the art so as to adapt the invention or parts thereof to other presses, without departing from the principle of the invention and the scope of the appended claim.

I claim:

The combination with means for separating and removing the top sheet from a pile of sheets, of a platform, a paper elevator comprising supports for said platform, a shaft, cables between the latter and the said supports to raise the same, a ratchet for rotating said shaft, a pawl for operating the ratchet, a feeler member for causing said pawl to engage the ratchet, means for supporting said feeler member to contact with the top sheet of the pile, devices for maintaining said feeler member out of contact with the paper while the top sheet is being separated and removed therefrom, means mounted on the said separating and removing means for operating said maintaining means away from the feeler member and other means on said separating and removing means for operating the said ratchet.

LEWIS E. MORRISON.
